HOUSE

Donald J. Scholz, Toledo, Ohio, assignor to Scholz
Homes, Inc., Toledo, Ohio, a corporation of Ohio

Filed Sept. 28, 1960, Ser. No. 62,292

Term of patent 14 years

(Cl. D13—1)

FIG. 1 is a front perspective view of a house embodying my new design;

FIG. 2 is a front elevational view of the house;

FIG. 3 is a top plan view in reduced scale;

FIG. 4 is a rear elevational view of the house;

FIG. 5 is an elevational view showing the left side of the house; and

FIG. 6 is an elevational view of the house's right side.

For convenience of illustration only parts of the brick surface and the shingle roof have been shown in the several views on the drawing. It is to be understood that these surfaces continue throughout the plain areas shown.

The design is characterized by the front of the house as illustrated most clearly in FIGS. 1 and 2.

I claim:

The ornamental design for a house, as shown and described.
